TOGGLE SWITCH

Oscar H. Hasselbaum, Arlington, Mass., assignor
to Joseph Pollak Corporation, Dorchester,
Mass., a corporation of Massachusetts

Application May 12, 1949, Serial No. 92,880

5 Claims. (Cl. 200—67)

1

The present invention relates to a toggle switch which may be used as a single pole, single throw switch or as a single pole double throw switch, or for other types of switch combinations.

A purpose of the present invention is to make a durable, light, quick-acting, highly current capacity toggle switch which can be manufactured very simply and cheaply and have a long life with constant and uniform performance.

In the present invention, a pivoted contact plate is employed which is operated by the toggle lever between the points of pivot for swinging the plate from one side of the dead center to the other, the plate making electrical contact as it comes to rest against the contact stop. In addition to this, however, the contact stop is provided with arms extending forwardly in the direction of swing of the pivot plate so that before the plate comes to a stop, a wiping spring contact has already been made with a portion of the stop or terminal contact. The making of a wiping contact in this way has the advantage that a clean metal-to-metal electrical contact may be made so that even though a dirt particle or insulating film may find itself between the plate and the fixed part of the stop contact, a full and good electrical contact will be made at all times which will avoid arcing or heating in the switch.

A further advantage of the present construction is that when the swinging plate is moved away from the stop contact, electrical connection is still maintained until the moving or swinging plate has attained such acceleration that a quick break results between the plate and the wiping contact.

Toggle switches of the present design have proved to be highly satisfactory and do not arc even though carrying a load far in excess of what a toggle switch of the same general type would ordinarily be rated. Other and further advantages of the present invention are to be found in the constructional features, assembly, the simplicity of construction and the use of few parts which are sturdy and well-wearing. It should also be noted that in the present invention, the swinging contact plate which connects with one of the terminals of the switch is always connected with the terminal by a spring pressure connection which makes it impossible for arcing to occur through the pivoting points of the plate. The failing of many pivoting switches is caused when resistance builds up through the pivoting connection, sometimes fusing the pivot and the supporting bearing together or causing the pivot to break or burn off completely, in both of which

2

cases the switch of course becomes inoperative and useless.

Without further describing the merits and advantages of the present invention, the invention will be described in connection with the drawings annexed hereto in which:

Figure 1 shows a perspective view of the switch with parts indicated in fragmentary section.

Figure 2 shows a central vertical longitudinal section taken substantially in a position of the switch shown in Figure 1.

Figure 3 shows a section taken substantially on the line 3—3 of Figure 2.

Figure 4 shows a plan view of the switch with the cover removed and,

Figure 5 shows a central section taken substantially on the line 5—5 of Figure 2.

In the arrangement indicated in the figures, the electrical contacts are mounted on an insulating base 1 which is provided with a shoulder 2 running around the upper surface of the periphery of the base and in which a metallic or other suitable cover 3 may rest. The cover may have downwardly projecting prongs 4 engaging grooves 5, 5 in the base 1 for the purpose of holding the cover and base together. The prongs 4 will, of course, be crimped over the insulating base for holding the two elements tightly together. At either side of the center of the insulating base are mounted terminals 6, 6 which are riveted to the base by means of rivets 7. On the inside of the base, the rivets 7 also hold the fixed contact elements 8, 8 which may be formed from a single piece of flat stock. These fixed contact elements comprise an L-shaped section 9 with the short turned-up end 10 which serves as the contacting stop portion for the moving contact plate as will be explained later. The element 8 also has two side arms 11 which also have the shape of the letter L, but in one plane. These sections 11 are bent up from the base portion 12 of the L-shaped section 9 at the side edges with the long portion of the L 11 extending beyond the turned-up section 10. The rivets 7 are positioned towards the rear end of the section 12 so that there is some springiness to the section 9 and also some to the section 11. The springiness in the L-shaped section 9 softens the contact of the switch plate against the section 10, while the springiness in the L-shaped arm 11 permits the plate to make a good wiping contact on the inner surface of the arm 11 as the swinging contact plate comes in contact position. The swinging contact plate mentioned above is shown at 13. This contact plate is pivoted in a cradle 14 which

is fixed to the insulating base 1 by means of the rivet 15 which on its external side also holds the terminal connector 16. The cradle 14 is C or channel shaped with recesses 17 and 18 in the top edges of the upright side elements 19 and 20 of the cradle.

The recesses 17 and 18 are aligned with one another and receive the outwardly projecting bosses or pivots 21 and 22 extending from the contact plate 14. The contact plate 14 has the shape of a letter W with the pivot points 21 and 22 extending from the outside of the outer arms of the W in the same plane as the contact plate at the top of the arms. Since the greater part of the contact plate is below the line of pivot, the plate in the position shown in the drawings hangs downwards resting easily in the recessed bearings 17 and 18. The lower part 23 of the contact plate is of such a width that when it is swung into position against the element 10, the side edges of the section 23 will wipe the upwardly extending arms 11 and make a good contact with them. As has been previously stated, the arms 11 may have sufficient spring so that slight pressure will be exerted by the arms against the edge of the section 23 of the wiping contact plate. The rivet 15 also holds the U-shaped spring member 24, the upwardly bowed sides 25 and 26 of which exert a spring tension against the ends of the pivots 21 and 22. The cradle 14, the wiping contact plate 13 and the U-shaped spring 24 are all electrically connected together but since, in the swinging of the wiping plate 13 the contact in the bearing surfaces or recesses 17 or 18 will change from point to point during the swinging of the wiping contact plate, a good electrical contact is maintained by the tension against the wiping plate at the end of the pivot connecting bosses 21 and 22. As will be noted from Figure 5, these bosses are quite high and therefore furnish a considerable contact surface with the spring element 25 and 26.

An operating lever 27 which may be provided with a spherical head 28 is mounted on the top of the cover 3 in a housing 29 which permits the lever to swing with a free motion in a plane perpendicular to the line of the pivot of the wiping contact. Extending from the spherical ball 28 is an insulating prong 30 which rides on a cap 32 which in turn sets into the top of a helical spring member 31 which is pressed down by the housing 29 on the central boss 33 of the W-shaped contact plate. This pressure gives the snap to the switch action so that when the lever is swung beyond dead center, it will snap over the rest of the way. This provides the toggle arrangement for the operation of the contact plate from a position at one side of the dead center to that of the other side of the dead center.

When the operating lever 27 is moved the contact plate 13 will tend to swing in the opposite direction, the arm 27 turning the wiping plate until it reaches a position beyond or approximately at the dead center, after which the helical spring 31 will cause the wiping contact to snap over into the opposite position from which it was before the lever 27 was moved. The switch illustrated in the drawings is a single pull double throw switch and the wiping contact is moved from the contact stop 10 on one side to the contact stop 10 on the other side. As the wiping contact leaves the contact stop 10, the contact is still continued through the same terminal until the end of the wiping contact has left the arm 11. It is noted in the drawings that the arms 11 are

carried forward to a position somewhat close to the dead center. As a result of this, electrical contact is continued until the wiping contact plate 13 has attained the acceleration and position necessary for it to snap to the other side. As a result of this expedient the breaking of the contact is made exceedingly rapid so that there is little chance for an arc to begin or last. In the same way also, the contact is made when the contact arm is moving quite rapidly by contact between the edge of the wiping contact arm and the upright spring members 11.

An additional advantage provided by the arm 11 engaging with the side of the contact members is that the wiping contact is held firmly in place at the end of its motion and even though there may be a tendency of chattering in the operating lever, the contact arm will be held firmly in position by the tension exerted against its edges by the spring arms 11. A mounting plate 34 may be carried at the top of the housing for mounting the switch on a panel, and as a protection against moisture getting into the side of the case a rubber collar 35 may be used over the operating lever 27 and the enclosing housing 29. The pivoting of the operating lever 27 is shown as a universal joint with the spherical pivoting member 28. Since in the arrangement shown the moving contact arm is only oscillated in pivots 21 and 22, the operating lever may also be pivoted in a pivot which would allow only motion in the direction perpendicular to the pivot line between the pivots 21 and 22.

Having now described my invention, I claim:

35 1. A toggle switch of the type described having a pivoted contact lever, means providing a toggle action for operating said pivoted lever, said lever comprising a plate element having pivot suspension points at each end with means in between for engaging said toggle acting means, means having recesses on their surfaces for supporting and engaging said pivot points, spring means bearing against the ends of said pivot points at the end of said recess means and contact means positioned to engage said pivoted lever to complete an electrical circuit.

2. A toggle switch of the type described having a pivoted contact lever, means providing a toggle action for operating said pivoted lever, said lever comprising a plate element having pivot suspension points at each end with means in between for engaging said toggle acting means, means having recesses on their surfaces for supporting and engaging said pivot points, spring means bearing against the ends of said pivot points at the end of said recess means and contact means having a portion positioned to engage said lever during its motion and another portion against which said lever comes to rest.

60 3. A toggle switch having a plate in a general W shape with pivoting points extending outward at the top of the arms of the W in alignment with one another, a cradle element having a recess wherein the plate can swing with shallow recesses at the top edge of the cradle to receive the pivot points, spring elements positioned to press against the pivot points at the outer sides of said cradle at both ends of the plate, toggle elements positioned to act on the center hump of the W for swinging said plate beyond the dead center and contact means positioned to engage said plate in its swing to make an electrical contact.

70 4. A toggle switch having a plate in a general W shape with pivoting points extending outward

at the top of the arms of the W in alignment with one another, a cradle element having a recess wherein the plate can swing with shallow recesses at the top edge of the cradle to receive the pivot points, spring elements positioned to press against the pivot points at the outer sides of said cradle at both ends of the plate, toggle elements positioned to act on the center hump of the W for swinging said plate beyond the dead center and contact means having an element positioned to limit the swing of said plate and make contact therewith with a portion of said element positioned to engage in wiping contact with the edge of said plate as it swings to rest.

5. A toggle switch having a plate in a general W shape with pivoting points extending outward at the top of the arms of the W in alignment with one another, a cradle element having a recess wherein the plate can swing with shallow recesses at the top edge of the cradle to receive the pivot points, spring elements positioned to press against the pivot points at the outer sides of said cradle at both ends of the plate, toggle elements positioned to act on the center hump of the W for swinging said plate beyond the dead 20 25

center and contact means having an element positioned to limit the swing of said plate and make contact therewith with a portion of said element positioned to continue in wiping contact with the edge of said plate while the plate is accelerating away from the portion limiting its swing.
